UNITED STATES PATENT OFFICE.

CHARLES E. CATHER, OF WORCESTER, MASSACHUSETTS, ASSIGNOR TO UNITED STATES ENVELOPE COMPANY, OF WORCESTER, MASSACHUSETTS, A CORPORATION OF MAINE.

ADJUSTABLE CUTTER FOR ENVELOP-BLANKS.

No. 863,588.

Specification of Letters Patent.

Patented Aug. 20, 1907.

Application filed March 18, 1907. Serial No. 362,815.

To all whom it may concern:

Be it known that I, CHARLES E. CATHER, a citizen of the United States, residing as Worcester, in the county of Worcester and Commonwealth of Massachusetts, have invented a new and useful Improvement in Adjustable Cutters for Envelop-Blanks, of which the following is a specification, accompanied by drawings forming a part of the same, in which—

Figure 1 is a top view of a cutter embodying my invention. Fig. 2 is an end view of the same.

Similar reference letters and figures refer to similar parts in the different views.

My invention relates to the improvements in the dies or cutters used to form envelop blanks, whereby I obtain a single cutter which forms the envelop blank at one operation, and which is also adjustable to different sizes or descriptions of envelopes, and comprises the improvements herein described and pointed out in the annexed claims.

Referring to the accompanying drawings 1 is the cutter, by means of which the seal flap and a portion of the end flap of the envelop is cut, and the angular cutters 2 and 3 form the reentrant angles or corners at the body of the envelop between the end and back flaps and also portions of the end and back flaps. The cutters are formed of steel or other suitable material. The cutter 1 and the angular cutters 2 and 3 are perforated to receive screw bolts 4, 4, each of the bolts having fixed collars 5, 5 against which the ends 6, 6 of the cutter 1 are held by nuts 7, 7. The angular cutters 2 and 3 are adjustably held on the bolts 4 by nuts 8, 8 and 9, 9. The opposite ends 10 and 11 of the angular cutters 2 and 3 are perforated to receive a screw bolt 12, which is provided with a fixed collar 13 against which the end 10 of the cutter 2 is held by a nut 14. The cutter 3 is adjustably held in the bolt 12 by nuts 15 and 16.

The paper from which the envelop blanks are to be formed is cut in any convenient shape with the sides 40 of the paper, designed to form the side flaps, arranged to be intersected by the cutters 1, 2 and 3 and the end designed to form the back flap arranged to be intersected by the cutters 2 and 3.

The paper from which the blank is to be cut is shown 45 in Fig. 1 by the broken lines *a*, *a*, *a*, *a* representing a rectangular shaped piece of sufficient length to form the seal and back flaps and of sufficient width to form the side flaps of an envelop blank when shaped by the cutters 1, 2 and 3.

A stack of paper of the rectangular shape shown by 50 the broken lines *a* is placed upon a cutting table and the cutter is placed upon it in position to cut the seal flap *b* by that portion of the cutter 1 lying between the angles 17 and 18. The portions of the cutter 1 lying on the outside of the angles 17 and 18 cut one edge of 55 each side flap *c*, *c*, the other edge of which is cut by the portions 19 and 20 of the angular cutters 2 and 3. The two sides of the back flap *d* are cut by the portions 21 and 22, of the cutters 2 and 3.

The envelop is formed by folding the side flaps on 60 the broken lines *e*, *e*, the back flap on the broken line *f* and the seal flap on the broken line *g*.

The adjustment of my improved cutter is made as follows:—To change the distance between the seal and back flaps the angular cutters 2 and 3 are adjusted on 65 the bolts 4 toward or away from the cutter 1; to change the distance between the side flaps the cutter 3 is adjusted toward or away from the cutter 2 and a cutter of different length is substituted for cutter 1. In this way the same die may be used for different sizes and 70 descriptions of envelopes with the necessity only of changing cutter 1.

I claim,

1. A die for cutting envelop blanks, consisting of a cutter for forming the seal flap and portions of the end flaps, 75 a pair of angular cutters for forming the angles between the end and back flaps and portions of said end and back flaps, means for adjusting said pair of angular cutters toward or away from said seal flap cutter, and means for adjusting said pair of angular cutters toward or away from 80 each other.

2. A die for cutting envelop blanks, consisting of a cutter for forming the seal flap and portions of the end flaps, a pair of angular cutters for forming the angles between the end and back flaps and portions of said end and back flaps, adjustable connections between the seal flap cutter and one end of each of said pair of angular cutters, whereby said pair of angular cutters may be adjusted toward or away from said seal flap cutter, and an adjustable connection between the other ends of said pair of angular cutters, whereby said pair of cutters may be adjusted toward 90 or away from each other.

3. A die for cutting envelop blanks, consisting of a cutter for forming the seal flap and portions of the end flaps, 95 a pair of angular cutters for forming the angles between the end and back flaps and portions of said end and back flaps, screw bolts between the seal flap cutter and one end of each of said pair of angular cutters, and a screw bolt between the other ends of said pair of angular cutters.

Dated the 15th day of March 1907.

CHARLES E. CATHER
